UNITED STATES PATENT OFFICE

160,181

DECORATIVE DRAPERY SUPPORTING FIXTURE

Thomas F. Krumm, Toledo, Ohio

Application May 17, 1948, Serial No. 146,410

Term of patent 7 years

(Cl. D21—2)

To all whom it may concern:

Be it known that I, Thomas F. Krumm, a citizen of the United States, residing at Toledo, county of Lucas, and State of Ohio, have invented a new, original, and ornamental Design for a Decorative Drapery Supporting Fixture, of which the following is a specification, reference being had to the accompanying drawing, forming part thereof.

In the drawing,

I claim:

The ornamental design for a decorative drapery supporting fixture, substantially as shown.

THOMAS F. KRUMM.
